LOOP PILE CUTTER

Hurl W. Penman, Bloomsburg, Pa., assignor to The Magee Carpet Company, Bloomsburg, Pa., a corporation of Pennsylvania

Application September 23, 1958, Serial No. 762,757

13 Claims. (Cl. 139—46)

This invention relates to a loop pile cutter for a gauge type loom.

It is an object of the invention to provide a series of cutting blades co-acting with the gauges of a loom to cut the pile loops formed on the gauges.

A further object of the invention resides in providing a series of oscillating cutting blades associated with the gauges of a loom operable to move into cutting engagement with the loops formed on the gauges as the loops move along the gauges in a direction opposite to the movement of the cutters.

A still further object of the invention resides in providing gauges having grooved loop forming portions with oscillating cutters operable in the grooves to cut the loops formed thereon.

Another object of the invention resides in providing a cutting mechanism having an oscillating shaft extending transversely of the loom above the forward ends of the gauges having a series of removable cutting blades for co-action with the gauges to cut the loops formed thereon.

Other objects and advantages of the invention will be apparent during the course of the following specification.

In the accompanying drawings forming a part of this specification and in which like numerals are employed to designate like parts throughout the same,

Fig. 1 is an end elevational view of the cutting mechanism applied to a gauge loom partly in section.

Fig. 2 is a fragmentary top plan view of the cutter shaft and one of the end bearings,

Fig. 3 is a cross sectional view of the cutter shaft and fragmentary longitudinal section of the loom gauge,

Fig. 4 is a detail fragmentary view of the cutter shaft with the blades removed,

Fig. 5 is a fragmentary elevational view of the cutter shaft showing the clamping plates for holding the blades,

Fig. 6 is a sectional view taken on line 6—6 of Fig. 5,

Fig. 7 is a diagrammatic view of the drive mechanism for the cutter shaft, and,

Figs. 8, 9 and 10 are views of the intermediate bearings for the cutter shaft.

In the drawings wherein for the purpose of illustration a preferred embodiment of the invention is shown the numeral 5 denotes generally the pile forming mechanism of a gauge loom such as disclosed in the application of Orrin J. Park et al., Serial No. 572,657, now U.S. Patent No. 2,896,671. In this type of loom a slide bar 6 mounted in slide rails 7 reciprocates transversely of the loom and supports an oscillating shaft 8 carrying a frame 9 on which are mounted a series of arms 10 having apertures 11 at their free ends to receive the pile yarns 12. As the shaft 8 oscillates the arms 10 carry the yarns 12 into and out-of the ground warps 13, the yarns being tied into the ground warps by weft shots in the usual manner. The arms 10 swing downwardly and upwardly on one side of the fixed gauges 14 and then downwardly and upwardly on the opposite side of the gauges

2

thus carrying the pile yarns across the top edge of the gauges forward of the shoulder 15 to form pile loops 16 on the reduced forward portion 17 of the gauges. Attached to the free end of the portion 17 is a U-shaped extension 18 the upper edge of which is inclined downwardly in a forward direction, as at 19.

A cutter shaft 20 extends transversely of the loom above the extensions 18 of the gauges being mounted in end bearings 21 attached to a cross bar 22 supported by standards 23. The cutter shaft mounts a series of cutting blades 24 which are semi-circular in shape. The blades are removably mounted in slots 25 formed in shaft 20 so that the curved cutting edge 26 projects beyond the periphery of the shaft and enters the groove in the extension 18. Upon oscillation of shaft 20 the cutting blades swing back and forth to cut the pile loops as they move forward along the gauges. A series of apertures 27 extend transversely of the shaft 20 in communication with the slots 25 to receive the stems 28 projecting from the straight edge of the blades 24. The stems extend from the blades slightly off center so one end of the blade projects a greater distance from the periphery of the shaft than the other end. The free ends of the stems are notched to receive the clamping plates 29 seated in the rabbet 30 formed in the shaft and are removably held in clamping position by screws 31.

The end bearings 21 are mounted on cross bar 22 by brackets 32 including a cross member 33 having transverse openings to receive fastening screws 34. An adjusting screw 35 extends vertically through the cross member 33 in bearing engagement with a plate 36 below the cross member to permit limited vertical adjustment of the bearings. A series of intermediate bearings are provided between the end bearings which include a cross member 37 secured to the cross bar 22 in the same manner as the end bearings. The cross member 37 is formed with a projecting hanger 38 which is slotted, at 39, to form a series of spaced bearings 40 which are relatively thin so as to fit between the cutter blades on the shaft 20.

Any suitable mechanism may be provided for oscillating shaft 20, such as shown in Fig. 7, wherein the shaft is provided at both ends with crank arms 41 connected by a connecting rod 42 with a reduced crank arm 43 mounted on the ends of a drive shaft 44 which is driven by a motor or other suitable driving means.

In operation, the pile loops 16 are formed over the forward portion 17 of the gauges 14 by the to and fro movement of the yarn carrying arms 10 and as the fabric being woven moves forwardly the loops slide forwardly over the extension 18 of the gauges. As the loops move forwardly the shaft 20 is oscillating to swing the cutting blades 24 and the oscillation of shaft 20 is so timed that when the loops move onto the extensions 18 of the gauges the cutters are swung in a direction opposite to the movement of the loops and upon entering the grooves of the extensions sever the loops on the extensions. When a blades swing in the opposite direction the uncut loops on the gauges move forward onto the extensions to be cut during the next cycle of operation of the blades. Thus, it is seen that when the blades swing in a cutting direction a series of loops on the gauges are severed and while the blades are swinging in a non-cutting direction the next series of loops to be cut are advanced along the gauges over the extensions at their ends.

Since the extension which supports the loops is U-shape in cross section the loops formed thereon are stretched across the top edges so that the bight portion of the loops is severed by the cutters in a perpendicular plane providing tufts with even ends.

Having thus described my invention, I claim:

1. In combination with a gauge type loom for weav-

ing pile fabrics, a shaft extending across the gauges having a series of transverse slots, cutter blades mounted in said slots and extending into grooves formed in the upper edges of the gauges, and means for oscillating said shaft to rock said cutter blades to cut the pile loops formed on the gauges.

2. In combination with a gauge type loom for weaving pile fabrics having gauges with loop forming portions at their ends of U-shape in cross section, a shaft extending across the loop forming portions of the gauges having a series of transverse slots, arcuate cutting blades removably fitted in said slots and projecting beyond the periphery of said shaft into the loop forming portions of the gauges, and means for oscillating said shaft to rock said cutting blades to cut the loops formed on the gauges.

3. In combination with a gauge type loom for weaving pile fabrics having gauges with loop forming portions at their ends of U-shape in cross section, a shaft extending across the loop forming portions of the gauges having a series of transverse slots, arcuate cutting blades disposed in said slots and projecting beyond the periphery of said shaft into the loop forming portions of the gauges, stems integral with said blades extending through apertures formed in said shaft and intersecting said slots, means removably securing said blades in said slots, and means for oscillating said shaft to rock the cutting blades to cut the loops formed on the gauges.

4. In a gauge type loom for weaving pile fabrics, a plurality of gauges having loop forming portions with grooves in their upper edges opening through the free ends thereof, the upper edge of the free ends being inclined downwardly and a series of cutters disposed adjacent the free ends and movable longitudinally in the grooves in a direction opposite to the direction of movement of the loops along the loop forming portions.

5. In combination with a gauge type loom for weaving pile fabrics having gauges with loop forming portions at their free ends provided with grooves in their upper edges, a shaft extending across the loop forming portions of gauges, means for oscillating said shaft, and a series of blades mounted on said shaft having curved cutting edges adapted to move in the grooves of said gauges, said blades having an axis of rotation eccentric to the axis of rotation of said shaft.

6. In a gauge type loom for weaving pile fabrics, a plurality of gauges having loop forming portions at their free ends, U-shaped extensions attached to the free ends of said gauge wires, a series of rockable cutter blades disposed above and projecting into said extensions, and means for rocking said blades to cut the loops formed on said gauges.

7. In a gauge type loom as described in claim 6 wherein the upper edge of said extensions are inclined downwardly at their free ends.

8. In a gauge type loom for weaving pile fabrics, a plurality of gauges having loop forming portions at their free ends provided with grooves in their upper edges, a shaft extending across the loop forming portions of said gauges above the grooves having a series of transverse slots, a series of blades mounted in said slots having

curved cutting edges projecting into the grooves of the loop forming portions of said gauges, said blades having an axis of rotation eccentric to the axis of rotation of said shaft and means for oscillating said shaft and blades.

9. In a gauge type loom for weaving pile fabrics, a plurality of gauges having loop forming portions at their free ends provided with grooves in their upper edges, a shaft extending across the loop forming portions of said gauges above the grooves, a series of blades mounted transversely of said shaft having curved cutting edges projecting into the grooves of the loop forming portions of said gauges, adjustable brackets supporting said shaft for raising and lowering said blades, and means for oscillating said shaft and blades.

10. In a gauge type loom for weaving pile fabrics, a plurality of gauges having loop forming portions provided with grooves in their upper edges, a shaft extending across the loop forming portions above the grooves having a series of transverse slots, a series of blades mounted in the slots of said shaft with one end extending a greater distance from the end of the slot than the other end, said blades having curved cutting edges projecting into the grooves of the loop forming portions of said gauges, and means for oscillating said shaft and blades.

11. In a gauge type loom as described in claim 10 wherein said blades are removably mounted in said slots.

12. In a gauge type loom for weaving pile fabrics, a plurality of gauges having loop forming portions provided with grooves in their upper edges, a shaft extending across the loop forming portions above the grooves having a series of transverse slots, a series of arcuate blades mounted in said slots and projecting from the periphery of said shaft into the grooves of the loop forming portions of said gauges, said blades projecting from one end of said slots for a greater distance than at the other end, stems integral with said blades extending through said shaft, means carried by said shaft for engagement with said stems to secure the blades in said slots, and means for oscillating said shaft and blades.

13. In a gauge type loom for weaving pile fabrics, a plurality of gauges having pile forming portions provided with grooves in their upper edges, a rotatable shaft extending across said gauges above the loop forming portions, a series of curved blades mounted transversely of said shaft having their axis of rotation eccentric to the axis of rotation of said shaft, said blades projecting from said shaft into the grooves of the loop forming portions of said gauges, and means for oscillating said shaft and blades.
